(57) **CLAIM**

We claim the ornamental design for a portable computer connection terminal with keyboard, as shown and described.

DESCRIPTION

FIG. 1 is a front perspective view of a portable computer connection terminal with keyboard of the present invention; FIG. 2 is a rear perspective view thereof; FIG. 3 is a rear perspective view with the connect part moved thereof;

FIG. 4 is a front view thereof;

FIG. 5 is a rear view thereof;

FIG. 6 is a first side view thereof;

FIG. 7 is a second side view thereof;

FIG. 8 is a top view thereof;

FIG. 9 is a bottom view thereof;

FIG. 10 is an enlarged cross-sectional view thereof taken along lines 10-10 in FIG. 4 and FIG. 6 and FIG. 8; and, FIG. 11 is a front perspective view thereof shown in an environmental use.

The broken lines in the drawings represent portions of the portable computer connection terminal with keyboard that form no part of the claimed design. Additionally, the dash-dot-dashed lines in the drawings define the boundaries of the claimed design.
